United States Patent Office

Des. 204,451
Patented Apr. 19, 1966

204,451

CHAIR

Ernest J. Straits, St. Charles, Ill., assignor to Interlake
Steel Corporation, a corporation of New York

Filed Nov. 16, 1964, Ser. No. 82,614

Term of patent 14 years

(Cl. D15—1)

Fig. 4.

Fig. 5.

Fig. 6.

FIG. 1 is a perspective view of a chair embodying the new design;

FIG. 2 is a front elevation of the chair shown in FIG. 1;

FIG. 3 is a top plan view of the chair;

FIG. 4 is a right side elevation of the chair;

FIG. 5 is a rear elevation of the chair; and

FIG. 6 is a bottom plan view of the chair.

The dominant features of my design reside in those portions shown in full lines on the drawing.

I claim:

The ornamental design for a chair, substantially as shown and described.
